UNITED STATES PATENT OFFICE.

JAMES S. STEWART, OF NEW YORK, N. Y., ASSIGNOR TO ANNIE STEWART, OF NEW YORK, N. Y.

ELECTRICAL APPLIANCE.

No. 920,786.

Specification of Letters Patent.

Patented May 4, 1909.

Application filed February 25, 1908. Serial No. 417,777.

To all whom it may concern:

Be it known that I, JAMES S. STEWART, a citizen of the United States, residing at the city of New York, in the borough of Manhattan and State of New York, have invented certain new and useful Improvements in Electrical Appliances, of which the following is a full, clear, and exact description.

10 My invention relates to a form of lamp receptacle or similar electrical appliance which is adapted for use for outdoor and interior purposes where the lamps are designed to be fixed to and supported by a solid frame or object such as an electric sign, the decorations or tower of a building, or the walls or ceiling thereof.

In my companion application, Serial No. 367,752, I have described a construction for 20 the above purposes in which a supplemental fastening device of sheet metal is employed in conjunction with a porcelain receptacle of special form, whereby the latter may be fastened in any desired relation. This application is very convenient, will not strain or break the porcelain, and complies with all insurance regulations. The present invention aims to secure a still further improvement in this regard, and to secure substantially 25 all the above functions without the use of any such specially constructed fastening device. With this object in view, I provide a form of receptacle or appliance which receives ordinary wood screws in such a way 30 that they act as fastening devices in conjunction with a surrounding sheet metal part.

From a broadly stated aspect, the present invention may therefore be said to comprise 35 a receptacle or appliance formed to receive ordinary screws on its exterior surface which engage a mere ordinary edge or part of a surrounding surface without any drilling or tapping, or any tool work whatever, except 40 initially forming the opening in which the receptacle is bodily inserted.

From another aspect, my invention comprises a particular form of indoor receptacle 45 particularly adapted for use in electric signs and banks of lamps where there is a single sheet metal supporting base common to all the lamps.

With these and other objects in view, my invention consists in the features of construc-

tion and combination, as hereinafter set forth and claimed.

In the drawings: Figure 1 is a sectional view of a lamp receptacle embodying the principles of my invention; Fig. 2 is a transverse sectional view of the same; Fig. 3 is a 60 sectional view on a plane at right angles to that of Fig. 1; Fig. 4 shows a slight modification embodying the outdoor receptacle; and Fig. 5 is a detail sectional view of the cap.

Referring to the drawings in which like 65 parts are designated by the same reference sign, 1 indicates the body of a receptacle of porcelain or other insulating material which may be of any suitable or desired form. I have shown two forms of receptacle of which 70 Figs. 1, 2 and 3 illustrate a type adapted for indoor use, while Fig. 4 shows an outdoor receptacle.

2 indicates a head or rib, or other projection upon the body 1 and through which are provided a plurality of holes 3 preferably extending in parallel and equally spaced-apart relation about said body 1. The holes 3 extend completely through the head 2 of the receptacle in such a way that 75 they intersect the outline of the body 1. This relation is clearly shown in Fig. 1 in which both the body 1 and the head 2 are cylindrical, so that the holes 3 intersect the cylindrical outline of the body 1. The body 80 1 is grooved in alignment with said holes 3, the grooves being of substantially semi-circular or U-shaped transverse section corresponding to the substantial alignment of 85 their surfaces with the bore of holes 3. Each 90 of the grooves 4 is, however, slightly deeper than an exact semi-circle, preferably having a depth in practice about equal to two-thirds the complete diameter of the holes 3. This 95 relation fixes the position of said holes 3 in the head 2, which, it will be seen must have a position slightly inside of that which they would occupy if their axes exactly intersected the outline of the body 1. Toward the lowermost or innermost ends of the 100 groove 4, they become shallower by a gradual inclination 5, so that at their terminations, they may be actually less than the radius of holes 3 in depth.

7 designates a sheet metal or other supporting plate having a hole 8 of a form and size to closely receive the body 1 of the receptacle. The receptacle 1 being preferably

circular, a round opening of corresponding diameter will be provided in plate 7. The body 1 being inserted through this opening, it is merely necessary to insert ordinary wood screws through the holes 3, which pass downward and engage the interior edge of opening 8 between their threads at the points where the latter are exposed outside the grooves 4. As the screws are rotated right-handedly, (or tightened) they exert their ordinary screw action in conjunction with the edge of the hole 8, so that the body 1 is borne downward into tight and locking relation upon the plate 7 with the head 2 abutting or binding thereagainst. When the head comes into such abutting engagement on the plate 7, however, the points of the screws meet and ride upon the inclined surfaces 5. By this action, the points of the screws are wedged or thrown outward, and their exposed portions impelled into engagement with the edge 8 and bound thereagainst with a force which is doubly positive by virtue of the combined wedging action and the leverage obtained. It is obvious that these features of construction and these principles are equally applicable to the form of outdoor receptacle shown in Fig. 4, and having the usual leading-in wires 10 cemented in water-proof relation therein. The parts in Fig. 4 are accordingly denominated by the same reference characters as the corresponding parts of Fig. 1 and need not be again particularly described.

35 An additional feature of my invention relates to the internal construction and circuit-connecting means of the indoor sign receptacle shown in Figs. 1, 2 and 3. The cylindrical outline of the body 1 terminates at a flat face 15 from the center of which, there projects a square or non-circular protuberance 16.

17 designates a cap of circular outline corresponding to the body 1 and having a central hole adapted to fit over the protuberance 16.

18 designates lugs or wings integral with the body 1 and projecting outward from the face 15 at points on opposite sides of the protuberance 16 and diametrically opposite one another. The vertical height of these protuberances or wings 18 is such as to form shoulders 19 which limit the closure of the cap 17 upon the receptacle. The transverse extent of the lugs or wings 18 is correspondingly such as to fit the diameter of the internal cavity of the cap, so that the latter is effectively divided into two entirely separate chambers in this way.

60 20 designates circuit wires which pass across the face 15 on either side of the partition formed by the lugs or wings 18, the cap having notches 21 at points to permit this relation.

65 22 designates terminal screws received in

clips 23 and 24, of which 23 is electrically connected to the threaded shell 25 by a screw 26, while 24 is electrically connected to the central stud terminal 27 by a screw 28. These last described connections are similar to those of electrical appliances hitherto proposed by me, and in themselves do not constitute any part of the present invention.

The cap 17 is freely removable from the body 1 after which the circuit wires can be stretched in place, as shown in Fig. 2, and engaged beneath the terminal screws 22. The cap 17 is then applied with its notches 21 fitting over the circuit wires and the protuberance 16 projecting through its rear face. The cap may be secured in this relation in any desired way, but I prefer a bent wire or pin 30 passed through a hole 31 in the protuberance 16 at a point to tightly hold the cover in place. The cap is transversely grooved at 32 to receive said pin, being reinforced by ribs 33 on its interior face. The lugs or wings 18 are grooved on their upper edges to receive the ribs 33 which are angularly located to suit this purpose, so that the receptacle is made as compact as possible.

It is evident that the circuit connections are simply and efficiently made, and all parts which are of opposite polarity are completely separated by a continuous porcelain wall or surface. When the cover is in place all of the bare electrified metallic parts are covered up, and at the same time the circuit wires are supported at an adequately spaced distance from the metallic plate 7. These requirements are all important ones to be satisfied in practice with sign receptacles and other similar appliances.

105 What I claim, is:—

1. An electrical appliance comprising a body having grooves, and a head having screw holes from which said grooves extend.
2. An electrical appliance comprising a hard body having longitudinal grooves on its superficial outline adapted to receive wood screws to a transverse depth less than the outer diameter of the threaded portions thereof.
3. An electrical appliance comprising a porcelain body having longitudinal grooves extending inward from one end and adapted to receive wood screws to a depth less than the outer diameter of the threaded portions thereof.
4. In combination with a support having a hole, a porcelain body having grooves on its superficial outline extending inward from one end thereof, and screws received in said grooves with their heads bearing against said end of the body and their threaded portions engaging the edge of the hole in said support.
5. An electrical appliance comprising a

body having grooves on its superficial outline, and a head having screw holes from which said grooves extend.

6. In combination with a sheet metal support having an opening, a body fitting in said opening, and screws loosely received in said body and engaging the edge of said opening between the exposed portions of adjacent threads.

10 7. In combination, a sheet metal support having an opening, a body received therein and having grooves, and screws received in said grooves and engaging the edge of said opening at points only between the exposed 15 portions of adjacent threads.

8. An electrical appliance comprising a body having grooves on its superficial outline, and a head having screw holes from which said grooves extend, said grooves being shallower at their terminations by a 20 gradual inclination.

9. An electrical appliance comprising a body having grooves on its superficial outline, and a head having screw holes from 25 which said grooves extend, said grooves having a depth equal to substantially two-thirds the diameter of said holes, as and for the purpose set forth.

10. In combination, a sheet metal support having an opening, a body received therein and having grooves, said grooves becoming more shallow at their terminations by a 30 gradual inclination, and screws loosely received in said body and engaging the edge of 35 said opening between the exposed portions of adjacent threads, said screws resting on said inclined portion of said grooves when they are fully tightened in place.

11. An electrical appliance comprising a 40 cylindrical body having grooves on its superficial outline, and a head projecting annularly around said body and having screw holes from which said grooves extend.

12. An electrical appliance comprising a 45 cylindrical body having grooves on its superficial outline, and a head projecting annu-

larly around said body and having screw holes from which said grooves extend, said grooves being of less depth than the diameter of said holes.

13. An electrical appliance comprising a body having grooves on its superficial outline and a head having screw holes from which said grooves extend, said grooves having a less depth than the diameter of said 50 holes.

14. In combination, a support having an opening, a body of hard insulating material received therein and having grooves, and screws received in said grooves and engaging 60 the edge of said opening at the exposed portions of the threads.

15. An electrical appliance comprising a porcelain body having grooves, and a head having screw holes from which said grooves 65 extend, said grooves being of less depth than the diameter of said holes.

16. An electrical appliance comprising a porcelain body having an end face with a central protuberance integrally formed thereon, terminals on said end face, lugs or wings on said face and forming a continuous partition separating said terminals, a porcelain cap fitting thereover and centrally perforated to receive said protuberance, said protuberance having a transverse opening and a pin received in said opening to lock the cap in 70 place.

17. An electrical appliance comprising a body having an end face, terminals thereon, 80 a partition on said end face separating said terminals and having grooves on its top or exposed edge, a cap fitting thereover and having a transverse groove, and means in 85 said grooves for holding said cap in place.

In witness whereof, I subscribe my signature, in the presence of two witnesses.

JAMES S. STEWART.
